(57) **CLAIM**

I claim the ornamental design for a connector for data transmission, as shown and described.

DESCRIPTION

FIG. 1 is a perspective view of the connector for data transmission showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The present design relates to a connector for data transmission, wherein the connector for data transmission can connect SSD (solid state drive) which has a SATA Connector to USB ports.

The line part which connects both ends is capable of bending as needed.

The broken lines in FIG. 5 represent unclaimed environment only and form no part of the claimed design.
